Des. 1233

Isaac De Touché, of St. Louis, Mo,
Letters Patent No. 1233, dated April 24, 1860.

The schedule referred to in these Letters Patent and making part of the same.

To all whom it may concern:

Be it known that I, Isaac De Touché, of the City of St. Louis in the County of St. Louis and State of Missouri, have invented or produced a new and original Design for a Parlor Stove, and I do hereby declare that the following is a full, and exact description of the same, reference being had to the accompanying drawings, and to the letters of reference marked thereon, making a part of the Specification.

A. represents a perspective view of the Stove showing the front plate D, and the end plate C, with the door E. E.

The front plate D, consists of a principal ornament &c. &c. &c.

2

Des 1233

representing an ornamental shield in the Louis Quatorze style surmounted by a basket of flowers T.T. whilst underneath is a husk with berries K, two roses with leaves I,I,I, and other natural leaves M,M,M.

In the center of the principal ornament is a ribbon O, on which are the words "Mount Vernon No. 1." Beneath the principal ornament is a ribbon L.L, on which are the words "Bridge Beach & Co. St. Louis Mo" on each side of the principal ornament is a foliated scroll ornament H.H.H. The corners N.N.N. consists of alternate circular and over beads confined by flat bands, one overlapping the other. The ornamental configuration of the Back Plate is exactly the same as the Front Plate D.

The end plate B. consists of an ornamental shield P.P. similar in style to G. G. in plate D. but less ornate. In the center are the words "Design Pat'd 1860". Surmounting the shield is a basket of flowers Q.Q. closely resembling T.T. on plate D. R. is a ribbon.

The end plate C. nearly resembles Plate B. The ornamental shield S.S. is curtailed on each side, and below is added on each side a rose with leaves T.T.

Having thus described my design, for a Parlor Stove. What I claim as new therein, and desire to secure by Letters Patent is -

The ornamental configuration and Design of Parlor Stove herein described, as shown in the annexed drawings -
